UNITED STATES PATENT OFFICE.

FRANK KOPPLIN, OF CHICAGO, ILLINOIS.

WHEEL-HUB FLANGE.

1,080,011.

Specification of Letters Patent.

Patented Dec. 2, 1913.

Application filed November 11, 1912. Serial No. 730,669.

To all whom it may concern:

Be it known that I, FRANK KOPPLIN, a citizen of the United States, residing at Chicago, in the county of Cook and State of Illinois, have invented certain new and useful Improvements in Wheel-Hub Flanges, of which the following is a specification.

It has become more or less common to provide wheel hubs with annular metallic bands adjacent to the central portion thereof, these bands having outwardly extending flanges through which bolts are passed which clamp the front and back flanges closely against the inner ends of the spokes. These metallic bands with their outwardly extending flanges are commonly termed as a whole "flanges." The band portion may be comparatively short and the hub may be provided with a point band, or the band portion may be extended out to the outer end of the hub in which case it is of a somewhat tapered form, and the point band is dispensed with. The present invention relates to such hub protecting members and to the combination with the hub, or wooden central portion of a metallic reinforcing and protecting member.

The objects of the present invention are to increase the strength and effectiveness of such hub flanges or protecting devices; to combine with a hub, a front flange or protecting member having an inwardly extending ring or flange; and to provide such advantages and improvements as will be more fully described hereinafter.

In the accompanying drawings illustrating my invention, Figure 1 is a side view of a hub with a front flange embodying the principal features of this invention, parts being broken away or shown in section; and Fig. 2 is an end view as seen from the right hand end of Fig. 1.

As indicated in these drawings, 3 represents a hub of wood or other suitable material which is provided with mortises 4 for receiving the spokes. The hub is provided with a back flange 5 which may be made of any ordinary or preferred form of construction. It is also provided with a front flange 6 embodying the principal features of this invention. The outwardly extending parts

7 and 8 of these two flanges are provided with holes 9 to receive bolts for bolting them together and against the inner ends of the spokes. The tubular or cylindrical portion 55 10 of the flange 6 preferably extends out slightly beyond the end of the hub 3 and is provided with an inwardly projecting flange or ring 11. This ring or annular member is preferably made integral with the main 60 cylindrical portion 10 of the flange 6, but in some instances may be made separately and attached thereto by means of rivets or in any other suitable manner if desired. The inner face of the ring 11 is preferably beveled or curved substantially as indicated at 65 12 so that the inner edge of the ring is thicker than the outer edge thereof. By means of this arrangement the inner edge is strengthened and the inner face of the 70 ring may be made to fit closely against the outer end of the hub.

It will be readily seen that by means of my improved construction, the flange or metallic cylinder which fits around the outer 75 periphery of the hub is strengthened at its outer end to a great degree so that it will not be apt to be jammed or bent when the outer end strikes against any hard or unyielding object. With such hub flanges or 80 bands as heretofore commonly used, when the end of the hub struck some hard or unyielding object the band would be jammed in and, at times the end of the hub would be broken or pressed inwardly to such a 85 great extent that it would be impossible to unscrew the axle nut. With my protecting ring or inwardly extending flange, the end of the wood is protected to such an extent that it would be almost impossible to break 90 or injure the end of the hub, particularly if the flange is made sufficiently strong in proportion to the size of the hub.

Having thus described my invention what I claim and desire to secure by Letters Patent is:

1. A hub flange having an integrally formed flange or ring extending inwardly at one end thereof, said ring having a beveled or receding inner surface, whereby it 100 is thicker at its inner periphery than at its outer periphery.

2. The combination with a wooden hub, of a hub flange having an inwardly extending flange or ring at the end thereof, of substantially the same width as the wood at the end of the hub, the face of said ring

thicker than the outer portion and may come in contact with the wood before the outer portion engages with the same.

FRANK KOPPLIN.
